UNITED STATES PATENT OFFICE

2,471,593

CROSSARM LATHE WRENCH

Irvin E. Toye, Omaha, Nebr.

Application August 18, 1947, Serial No. 769,292

2 Claims. (Cl. 81—177)

1

This invention relates to combination tools for special purposes and more particularly it is an object of the invention to provide a tool particularly useful in the adjustment of lathes and the like.

Another object of the invention is to provide a tool as described capable of assuming a shape for providing great leverage for certain operations and capable of folding to a more compact and handy shape for use during other operations.

Still another object of the invention is to provide a tool as described which is extensible for reaching an adjustment point on a lathe or the like, from a distance.

Yet another object of the invention resides in the provision of a tool having in combination the said leverage and the said extensibility.

A further object of the invention is to provide a lathe wrench having a plurality of wrenching jaws upon a handle portion thereof and also having an arm portion foldable with respect to the handle portion, the arm portion also being provided with wrenching means thereon.

Other and still further objects and advantages of the invention will become apparent from the following detailed description of a preferred embodiment thereof.

In the drawings:

Figure 1 is a side elevation of the new tool in a folded position;

Figure 2 is a view-in-section taken along the line 2—2 of Figure 3;

Figure 2a is a view-in-section taken along the line 2a—2a of Figure 3;

Figure 3 is a frontal elevation of the new tool in folded position; and

Figure 4 is a side elevation of the tool in an unfolded position; an optional position of the handle portion thereof, with respect to the arm portion thereof, being shown in dotted lines.

The lathe wrench of this invention comprises a handle portion 10, preferably formed in the shape of a flat rectangular bar having wrenching jaws or notches 12, 14 and 16 extending therethrough in a direction transverse thereof.

The notches 12, 14 and 16 preferably have flat non-circular walls for engaging nuts, bolts and the like, as are commonly employed on lathes and similar machinery for facilitating the adjustment thereof. The jaws or notches 12, 14 and 16 are each of a different size for performing a different operation.

The handle portion 10 may also be provided with an opening 18 therethrough, the latter being of square or other non-circular shape, so that the walls thereof will be adapted for engaging other nuts and bolts and the like. The handle portion 10 is further provided with an elongated slot 30, disposed longitudinally therethrough from

2

the wide, flat sides thereof, the slot 30 being provided with two parallel side-walls.

The purpose of the slot 30 is for receiving an elongated arm portion 40 of the device, and the slot 30 is of such length and size with respect to the arm portion 40 that the latter may be received between the end walls of the slot 30 at times when the arm portion 40 is disposed in longitudinal alignment with the handle portion 10.

The arm portion 40 is provided with two parallel sides 42 and 44 which latter are spaced apart a slightly lesser distance than the parallel walls of the slot 30. Thus, the sides 42 and 44 of the arm 40 are respectively disposed opposite the parallel side walls of the slot 30. The sides 42 and 44 of the arm portion 40 are preferably each provided with a longitudinally disposed elongated recess 60, the recesses 60 being disposed in substantial parallelism with each other.

The arm portion 40 is provided with any suitable wrenching means secured thereto. Such means preferably comprises integral squared ends 70 and 72 which latter are for the particular purposes of engaging between the walls of the socket receptacles of jaws, lathe chucks or the like of complementary size.

The arm portion 40 is secured to the handle portion 10 by means now to be described. Such means includes the provision of a hole 80 extending completely through the handle portion 10 in a direction transverse with respect to the latter and at a right angle to the parallel side walls of the slot 30. The hole 80 is preferably of circular shape and is provided with a portion disposed on either side of the slot 30.

Two nibs 82 and 84 are respectively disposed extending partially into the respective portions of the hole 80 and are disposed partially protruding outwardly of the oppositely disposed parallel, longitudinal walls of the slot 30. The nibs 82 and 84 are preferably of circular shape in cross-section and are adapted to slide longitudinally of the hole 80.

Resilient means 86, preferably comprising two coiled compression springs, are disposed in the two respective portions of the hole 80 adjacent each of the nibs 82 and 84.

Two set screws 90 are provided and threadedly secured, one each, in the half-portions of the hole 80 and on opposite sides of the springs 86 from the nibs 82 and 84 for the purpose of regulating the urge of the springs 86 against respective ones of the nibs 82 and 84. The nibs 82 and 84 are oppositely disposed in axial alignment and are preferably circular and of widths similar to but very slightly less than the widths of the slots 60. The screws 90 are preferably of the headless countersinkable type.

An aperture 92 (see Fig. 2a), and similar to the

hole 80, extends through the handle 10 from the outer edge thereof to the adjacent wall of the slot 30. The purpose of the aperture 92 is to threadedly receive a screw 110 shown in Figures 3 and 4.

The screw 110 is adapted to bear against a third resilient means 94, preferably similar in all respects to the coiled spring 86. The third resilient means 94 is disposed in said aperture adjacent the screw 110. Also in said aperture, and on the other side of said third compression spring, a third nib 112 is disposed, the latter being shown in Fig. 2a.

The third nib 112 extends outwardly of the said aperture and is adapted to be received in one or the other of two like indentations 120.

The indentations 120 are disposed in the adjacent side 42 of the arm 40, with respect to the nib 112. Preferably the indentations 120 are of circular shape having rounded concave walls and the third nib is provided with a rounded convex outer end for engagement with the walls of the indentation 120.

The purpose of the third nib and the indentations 120 is so that at times when an operator causes the arm 40 to be disposed longitudinally in the slot 30, the third nib 112 will engage in one of the indentations 120 for holding the arm 40 in such position. The indentation 120 and the third nib are rounded so that an operator may easily cause the third nib to release the arm 40 to permit the latter to pivot with respect to the handle 10 for purposes later described, the third nib 112 at such times becoming disengaged from one of the indentations.

In operation, various wrenching adjustments on different parts of machinery can be made by using the notches 12, 14 and 16 and the non-circular opening 18 in a usual wrenching manner. At such times the arm 40 will be disposed longitudinally with respect to the handle 10 and will be received in the opening 30 thereof, being held in place by the engagement of the third nib 112, see Fig. 2a, with one of the indentations 120.

At times when it is desired to make an adjustment on a lathe chuck or the like, the arm 40 is placed in a transverse position with respect to the handle 10. The handle 10 may be placed at any desired position along the recess 60 of the arm 40 for causing the arm 40 to extend outwardly therefrom a sufficient distance for adjusting a lathe chuck at times when the material being worked on in the lathe protrudes outwardly alongside the lathe chuck.

This invention has provided a combination tool capable of assuming a shape for providing great leverage, capable of folding to a more compact shape, and capable of being extended outwardly sufficiently for reaching an adjustment point on a lathe or the like despite adjacent obstructions.

From the foregoing description, it is thought to be obvious that a wrench constructed in accordance with my invention is particularly well adapted for use by reason of the convenience and facility with which it may be assembled and operated, and it will also be obvious that my invention is susceptible of some change and modification without departing from the principles and spirit thereof and for this reason, I do not wish to be understood as limiting myself to the precise arrangement and formation of the several parts herein shown in carrying out my invention in practice, except as claimed.

I claim:

1. A lathe wrench comprising a handle portion provided with an elongated slot disposed therethrough, said slot having two oppositely disposed sidewalls and two oppositely disposed end walls, said handle portion having a hole extending therethrough in a direction transverse thereof, portions of said hole being disposed on either side of said slot; two nibs each being slidably disposed in a position extending partially into said hole and partially protruding outwardly of said oppositely disposed side walls of said slot; resilient means disposed in each of said hole portions adjacent said nibs; two set screws threadedly and adjustably secured to the walls of respective ones of said hole portions and on the opposite side of said resilient means from said nibs for regulating the pressure of said resilient means against respective ones of said nibs; and an elongated arm portion, said arm portion being of a length for receipt between said end walls of said slot at times when said arm portion is disposed in alignment with said slot, said arm portion having two parallel elongated recesses, the latter being disposed, one each, in opposite sides of said arm portion, said nibs being each partially received in respective ones of said recesses to permit said arm portion to pivot with respect to said handle portion and then to be moved in a direction transversely of said handle portion.

2. A lathe wrench comprising a handle portion provided with an elongated slot disposed therethrough, said slot having two oppositely disposed side walls and two oppositely disposed end walls, said handle portion having a hole extending therein in a direction transversely disposed with respect thereto, portions of said hole being disposed on either side of said slot; two nibs, each being respectively disposed in a position extending partially into a different one of said hole portions and partially protruding outwardly of said oppositely disposed side walls of said slot; an elongated arm portion, said arm portion being of a length for receipt between said end walls of said slot at times when said arm portion is disposed in alignment with said slot, said arm portion having two parallel elongated recesses, said recesses being disposed, one each, on the opposite sides of said arm portion, said nibs being each partially received in respective ones of said recesses to permit said arm portion to pivot with respect to said handle portion and then to be moved in a direction transversely with respect to said handle portion; means on said handle portion for releasably engaging said arm portion at the wall of said recess for maintaining said arm portion in parallelism with said handle portion at desired times; and resilient means for urging said nibs against said arm portion and outwardly of said portions of said hole respectively.
